Primary Examiner — Lilyana Bekic*Assistant Examiner* — Sharon S Oum(74) *Attorney, Agent, or Firm* — McGarry Bair PC(57) **CLAIM**

The ornamental design for a ceiling fan cage band, as shown and described.

DESCRIPTION

FIG. 1 is a top perspective view of a ceiling fan cage band showing our new design, shown in the environment of a ceiling fan;

FIG. 2 is a bottom perspective view thereof;

FIG. 3 is a top view thereof;

FIG. 4 is a bottom view thereof; and,

FIG. 5 is a side view thereof;

The broken lines illustrate environmental structure and form no part of the claimed design.

1 Claim, 5 Drawing Sheets(56)
